ADJUSTABLE BELT

Morton J. Sobel, Roslyn, N.Y.

Application February 27, 1956, Serial No. 568,102

4 Claims. (Cl. 2—322)

This invention relates to belts and, more particularly, to a novel belt provided with means for adjustably positioning a buckle along the buckle end of the belt in any one of several preset positions relative to the other end of the belt to thereby vary the effective length of the belt so that one belt may be used for several sizes of belts.

Belts are generally cut in accordance with different waist lengths, such as "36," "38," "40," for example, with some adjustment as to tightness or looseness being provided by adjustable positioning of the buckle along the free end of the belt. In the case of belts having a free end formed with a series of holes to receive a tongue or stud on the belt, the belt size is determined by the distance between the outermost cross bar of the buckle and the intermediate hole of the series, the number of holes usually being five and the length being measured to the middle or third hole.

To provide an adequate selection for customers with different waist lengths, a belt purveyor must stock a large number of different sizes of belts, as the amount of adjustment in any given size of belt, due to adjustment of the free end relative to the buckle, is insufficient to more than just barely accommodate the next size below or above such given size without there being either an excessive length of the belt free end projecting through the buckle or, alternatively, the free end just barely extending into operative relation with the buckle. While various means have been suggested for making belts adjustable in length, none have found commercial acceptance.

In accordance with the present invention, a belt is made to accommodate three or more given sizes by providing means on the buckle end for selectively and adjustably positioning the buckle at three or more set distances from the free end of the belt. For example, one belt can be readily adjusted or pre-set so as to be a size 38, size 40, size 36, and size 42, for example. Thereby the number of different sizes of belts required to be stocked is sharply reduced, such as by 75 percent or more.

More specifically, such adjustment as to size is provided by alternating male and female fastener elements arranged in alignment and preferably medially along the buckle end of the belt, with the first fastener element near the outer end of such buckle end of the belt and preferably a female element. The fastener elements are at pre-set substantially equal distances from each other so that, when the buckle end is inserted through a buckle and folded back on itself, engagement of a fastener element on the folded back portion with a mating fastener element on the flat portion will "set" the buckle at a pre-set distance from the free end of the belt to adjust the belt at a pre-set size.

Thus, with four snap fastener elements in male-female alternation, three size adjustments are provided. With six elements, for example, five sizes are provided, etc. The usual loop for receiving the folded belt end

2

may be "locked" between two pairs of interengaged fastener elements.

The adjustment feature is useable with any of the three common types of buckles (prongless or stud, tongue, and jewelry or box buckles) and with either a "straight" or a "contour" ("taper") belt.

For an understanding of the invention principles, reference is made to the following description of typical embodiments thereof as illustrated in the accompanying drawings. In the drawings:

Figs. 1 and 2 are inside elevation views of the buckle ends of belts embodying the invention;

Figs. 3, 5 and 7 are top plan views of the belt of Fig. 2 with a stud buckle attached thereto in the long, intermediate, and short position of the belt, respectively;

Figs. 4, 6 and 8 are inside elevation views of the belt of Fig. 2, corresponding respectively to Figs. 3, 5 and 7;

Fig. 9 is a top plan view of the belt of Fig. 2 with the free end locked around the loop;

Fig. 10 is an inside elevation view corresponding to Fig. 9; and

Figs. 11 and 12 illustrate the belt as used with a "tongue" and "box" buckle, respectively.

Referring to Fig. 1, a "straight" belt 10, in accordance with the invention, is illustrated as provided with a series of alternating female and male fastener elements 11—16 arranged at equal spaced intervals medially of the buckle end 17 of the belt. Belt 10 may be of any suitable material, such as natural or artificial leather, cloth, or plastic composition material, and the snap fastener elements 11—16 may extend completely through the belt or may have their outer ends concealed. The operative ends of the fastener elements are exposed on the inner side of the belt. In the usual manner, belt 10 may have a loop 18 thereon.

For the purposes of the invention, alternate snap fastener elements 11, 13, 15 may be female elements and intermediate snap fastener elements 12, 14, 16 may be male elements, or vice versa.

Also, while six fastener elements are illustrated, less than this number, for example four, or more than six may be used. With four fastener elements, the belt has three adjusted lengths, as will appear, and six fastener elements provide for five adjusted lengths of the belt.

Fig. 2 illustrates a "contour" or "taper" belt 10' differing from belt 10 only in that the buckle end 17' is narrower than the remainder of the belt.

Figs. 3 and 4 illustrate the belt 10' as adjusted for its longest length. In this case, belt end 17' is passed through a "stud" buckle 20 and looped around the inner end 21 of the buckle. Snap fastener element 11 is engaged with snap fastener element 12 so that a minimum length of end 17' is folded back on itself.

Figs. 5 and 6 illustrate belt 10' as adjusted to the next smaller waist size. Fastener elements 11 and 12 are engaged with fastener elements 14 and 13, respectively, and loop 18 may be "locked" between engaged fasteners 12—13 and 11—14.

Figs. 7 and 8 illustrate belt 10' as adjusted to its smallest size. In this position of the belt, fastener elements 15 and 16 are interengaged with folded end 17' extended through loop 18. In the position of Figs. 9 and 10, the extreme end of end 17' is folded back underneath itself through loop 18, and fasteners 11 and 13 engaged with fasteners 12 and 14, respectively.

The belt may be used with other types of buckles such as a "tongue" or "box" buckle. In Fig. 11, belt 10" is shown as having short slots 22 between adjacent snap fastener elements to receive the tongue 32 of a tongue buckle 30 whose inner bar 31 is received in the belt loop.

Fig. 12 shows a box buckle 40 attached to the loop of belt 10' by means of its securing ring 41.

While specific embodiments of the invention have been shown and described in detail to illustrate the application of the invention principles, it will be understood that the invention may be embodied otherwise without departing from such principles.

What is claimed:

1. An adjustable belt comprising, in combination, an elongated strip of belt material having a buckle end and a free end; a plurality of interengageable male and female fastener elements aligned, in alternation, longitudinally along the buckle end of the belt; and a buckle secured in the bight formed by folding said buckle end on itself and interengaging selected longitudinally adjacent mating male and female elements of said fastener elements; the effective length of the belt being adjustable, as to the distance of the buckle from the free end of the belt, in accordance with the selected distances of the interengaged longitudinally adjacent mating fastener elements from the buckle end of the belt. 15

2. An adjustable belt as claimed in claim 1 in which said buckle is a tongue buckle and said belt has relatively elongated tongue receiving slots between adjacent elements of said fastener elements. 20

3. An adjustable belt as claimed in claim 1 including a loop securable in adjusted position by said elements. 25

4. An adjustable belt comprising, in combination, an elongated strip of belt material having a buckle end and

a free end; a plurality of interengageable male and female fastener elements aligned, in substantially equi-spaced relation and in alternation, longitudinally along the buckle end of the belt; a buckle secured in the bight formed by folding said buckle end on itself and interengaging selected longitudinally adjacent mating male and female elements of said fastener elements; the effective length of the belt being adjustable, as to the distance of the buckle from the free end of the belt, in accordance with the selected distances of the interengaged longitudinally adjacent mating fastener elements from the buckle end of the belt. 5
